(57) **CLAIM**

The ornamental design for a vape device, as shown and described.

DESCRIPTION

FIG. 1 is a front elevational view of the vape device; FIG. 2 is a front perspective view of the vape device of FIG. 1; FIG. 3 is a left side elevational view of the vape device of FIG. 1; FIG. 4 is a right side elevational view of the vape device of FIG. 1; FIG. 5 is a top plan view of the vape device of FIG. 1; FIG. 6 is a rear elevational view of the vape device of FIG. 1; and, FIG. 7 is a bottom plan view of the vape device of FIG. 1. The broken lines in the drawings illustrate portions of the vape device that form no part of the claimed design.

1 Claim, 3 Drawing Sheets
